(57) **CLAIM**

The ornamental design for a quick thermometer, as shown and described.

DESCRIPTION

FIG. 1 is a perspective view showing our new design;
FIG. 2 is a rear view thereof;
FIG. 3 is a front view thereof;
FIG. 4 is a right side view thereof, the left side view being
a mirror image thereof;
FIG. 5 is a top view thereof; and,
FIG. 6 is a bottom view thereof.
The broken lines are for illustrative purposes only and form
no part of the claimed design.
